DESIGN FOR A CRUCIFORM PENDANT

Max Kronstadt, New York, N. Y.

Application July 12, 1939, Serial No. 85,961

Term of patent 3½ years

To all whom it may concern:

Be it known that Max Kronstadt, a citizen of the United States and resident of New York, in the county of New York and State of New York, has invented a new, original, and ornamental Design for a Cruciform Pendant, of which the following is a specification, reference being had to the accompanying drawing, forming part thereof, in which,

Fig. 1 is a front elevational view of a cruciform pendant embodying my new design;

Fig. 2 is a side edge view thereof; and

Fig. 3 is a top edge view thereof.

I claim:

The ornamental design for a cruciform pendant, substantially as shown.

MAX KRONSTADT.
